TRIODE VACUUM TUBE

Application filed January 27, 1925. Serial No. 5,073.

My invention relates to thermionic discharge devices and more particularly to cathode structures therefor.

An object of my invention is to construct a filamentary cathode member for a thermionic discharge device which is more resistant to the electrostatic forces which tend to bend and to destroy the filament.

Another object of my invention is to produce a self-supporting tungsten filament cathode structure.

Another object of my invention is to produce a double, looped filament, cathode in which the loops are supported at the bights thereof and also bound together at another point.

In prior construction of thermionic discharge devices, it has been customary to use looped filament cathodes. In devices adapted for the translation of high power, it has been found necessary to apply high voltages to such devices, usually ranging between 1,000 and 10,000 or more volts. At certain portions of the operating cycle of the device, this full voltage is impressed between the anode of the device and the filamentary cathode. Particularly in the case of thermionic discharge devices used for rectifiers without an interposed grid structure, double this voltage is applied between the anode and cathode at certain portions of the operating cycle. The filamentary cathode is made of tungsten and is, therefore, more rugged than would be the case if it were made of certain other metals. But in such devices, the filament is operating at an elevated temperature which may be more or less near to its softening point. It is, therefore, more readily subject to deformation than it would be at lower temperatures. A particularly high temperature is required in order to obtain as large an electron emission as possible to cause the device to function in the desired manner.

The electrostatic stresses involved under these operating conditions result in a deformation of the filamentary cathode, which may continue until the filament breaks, or until it touches another electrode and short circuits the device.

My invention provides a construction

whereby the electrostatic forces impressed upon the filament may be partially compensated by similar forces acting in an opposite direction. I obtain this partial compensation by a construction in which two looped filaments may be crossed at a point between the ends of the filaments and the bights of the loop and lashed together at the crossing point.

Other objects and structural details of my invention will be apparent from the following description when read in connection with the accompanying drawings, wherein:

Fig. 1 is a view in perspective of a form of filamentary cathode constructed in accordance with my invention,

Fig. 2 is a diagram of a portion of a filament according to my invention and indicating the stresses which are applied thereto,

Fig. 3 is a diagrammatic sketch of the structure of my invention also indicating the nature of the stresses applied thereto,

Fig. 4 is a view, partially in section and partially in elevation, of a device embodying a form of my invention, and

Fig. 5 is a plan view taken on the line V—V of Fig. 4.

Referring to Fig. 2, there is indicated diagrammatically a method of compensating the electrostatic forces according to a form of my invention which consists in positioning a filament diagonally within the cylindrical anode, whereby the resultant forces are in one direction at the bight ends of the filament and in another direction at the support end.

Fig. 3 shows a diagrammatic representation of the disposition of the electrostatic forces acting upon a pair of looped filaments positioned in the manner shown in Fig. 2. In Fig. 3 looped filaments 1 and 2 are provided positioned as in Fig. 2, with a spring supporting member 3. Binding members 4 which may be of any material capable of withstanding the operating temperature of the cathode, for instance, the cathode material itself, hold the filaments together at their crossing points. As indicated in Fig. 4, the points of intersection of the two filaments which are bound together by the members 4 are adjacent the respective

ends of the two filaments which are connected to the same inleading wires and which, accordingly, have the same polarity. This construction opposes the stresses upon one filament to those in an opposite direction upon another filament, and thereby reduces the effect thereof upon the filament. The filaments are connected in parallel to the supply leads, and the distance from the support wires to binding wires 4, being the same for each filament, the potential drop is the same, and the crossing point is an equipotential point.

In Figs. 1, 4 and 5 are shown filaments 1 and 2, a spring supporting member 3, and binding means 4 consisting of a wrapping of wire, preferably of tungsten. An anode 5 surrounds the filaments. A vitreous closure 6 is attached to the anode 5, by a seal 7. Closure 6 has a re-entrant portion 8 and a press 9 thereon through which are passed lead wires 11 and 12. To lead wires 11 and 12 are attached filament support wires 13, 14, 15 and 16 to the ends of which are attached the ends of filaments 1 and 2. The portion of my device so far described is adapted to be used either as a two-element rectifier or as a triode for various purposes.

If desired, a grid member may be interposed between anode and cathode as shown in Fig. 4 at 17. This grid is supported in any desired manner as by longitudinal wires 18 suitably secured to a supporting band 19, which surrounds a glass member 21 sealed to re-entrant portion 8 of the container 6. By this means, I am able to produce a self-supporting cathode structure which is resistant to the deforming effects of the electrostatic forces of the applied potential.

While I have shown only one embodiment of my invention in the accompanying drawings, it is capable of various changes and modifications without departing from the spirit thereof, and it is desired, therefore, that only such limitations shall be imposed thereon as are indicated in the prior art or indicated in the appended claims.

I claim as my invention:

1. A thermionic discharge device comprising a cathode having two looped filaments electrically connected in parallel, a pair of elastic supports engaging the bights thereof, said filaments crossing at a point between the ends and bights thereof and electrode means cooperating with said cathode.

2. A mount for a thermionic discharge device comprising a cathode having two looped filaments connected electrically in parallel, a pair of elastic supports engaging the bights thereof, said filaments crossing at a point between the ends and bights thereof, and binding means uniting said filaments at said point.

3. A thermionic discharge device comprising in combination an anode, and a cathode comprising a plurality of looped filaments,

lead wires therefor, supporting means for each of said filaments at three different points, one of said supporting means comprising an elastic hook engaging the bight of said loop, and binding means attaching said filaments together at equipotential points.

70

4. A thermionic discharge device including a cathode which comprises two looped filaments, each filament being supported at the three points of an isosceles triangle, said filaments being so supported with respect to each other that the plane determined by the three points of support of one filament intersects the plane determined by the three points of support of the other filament on a line between the ends of the filaments and the bights thereof, the bases of the said triangles being substantially parallel to each other and electrode means cooperating with said cathode.

75

5. A thermionic discharge device including a cathode which comprises two looped filaments connected in parallel, each filament being supported at the three points of an isosceles triangle, said filaments being so supported with respect to each other that the plane determined by the three points of support of one filament intersects the plane determined by the three points of support of the other filament on a line between the ends of the filaments and the bights thereof, the bases of the said triangles being substantially parallel to each other and electrode means cooperating with said cathode.

80

6. A thermionic discharge device including a cathode which comprises two looped filaments, the ends of one filament being supported by members spaced apart, the ends of the other filament being supported by members spaced apart and spaced away from said first members, the bight of each filament being on the side of the discharge device which is opposite the side in which its end supporting members are located and electrode means cooperating with said cathode.

85

In testimony whereof, I have hereunto subscribed my name this 21st day of January, 1925.

ILIA E. MOUROMTSEFF.
